UNITED STATES PATENT OFFICE.

GUSTAV SAALER, OF NEW YORK, N. Y.

PROCESS OF PURIFYING GASES.

No. 856,732.

Specification of Letters Patent.

Patented June 11, 1907.

Application filed December 27, 1906. Serial No. 349,692.

To all whom it may concern:

Be it known that I, GUSTAV SAALER, a subject of the German Emperor, residing at New York city, in the county of New York and State of New York, have invented new and useful Improvements in Processes for Purifying Gases, of which the following is a specification.

My invention is a process for purifying combustible gases so that they can be used in gas engines, and is particularly adapted to be applied as a continuous process to the purifying or washing of such gases in large quantities, for instance, as they come from blast furnaces, or other furnaces, and is so effective that thereby it is even possible to purify illuminating and producer gas practically perfectly.

My process consists first and as an initial step in cooling and thoroughly moistening the gas by passing it through a water shower, second in passing through a stream of spray, which is being continually broken up into fine spray or water-mist and driven directly against the stream of gas by any suitable means, such as a drum carrying inclined wings and rotated in an inclosing shell, whereby the saturation of the gas with water is insured and the heavier impurities extracted, third by forcing the gas successively through a plurality of veils or sheets of the water-mist so formed to extract the lighter impurities, and finally in drying the gas to the necessary extent, by separating the greater part of the moisture by said centrifugal force, whereby also perfect extracting of the impurities is insured. It will be understood that the gas is continuously and rapidly forced through the entire apparatus and subjected to all steps of the process in turn by any suitable power, such as a fan, and is always moving in an opposite direction to the water. The result of my process is a practically perfect purification, which before has been effected only imperfectly and to deliver a supply of such cleaned gas to the engine uniformly purified and at a constant pressure, whereby the necessity of a gas-holder is avoided. This initial step of simultaneously moistening and cooling the gas is very important because, thereby, the production of steam later in the process is avoided which would tend to carry forward fine impurities into the engine and because the impurities are thereby saturated with the water and made heavier, or, to some extent, dissolved

in or combined with the water, so that they are separated out by the centrifugal action of the machine. It thus makes easier the moistening of the gas in the second and third steps of the process. This preliminary moistening is also important because it promotes the purifying of the gases in the earlier part of the process and the centrifugal machine, leaving the last part of the process for drying or separating out the water. Therefore it will be understood that the more completely the gases can be initially cooled and moistened the better. Also as an incidental advantage, a substantial portion of the heavier impurities are washed out in this initial step, leaving less of the purification to be accomplished later in the process and the machine.

I am aware that it has heretofore been proposed to wash gases by forcing them through a rotary gas washer, in which a stream of water was broken up and driven in the opposite direction to the stream of gas, by means of spirally arranged wings on the exterior of a drum rotating within a casing. But such machines and processes have proved unsuccessful in practice because the gases, entering the gas washer in a heated condition converted more or less of the water into steam, whereby more or less of the fine dust and tar were carried forward into the pipes and the gas engine, seriously impeding, and often entirely stopping the engine. It has been said that it was desirable to introduce the gas into the washer as hot as possible, but this is absolutely wrong. These prior processes also were unsuccessful because they failed to moisten, or sufficiently moisten the gas; such initial moistening is essential to saturate the impurities, whereby they are rendered heavier and therefore more easily, as well as more perfectly purified. As there was not sufficient moistening in the old process, the gas was imperfectly purified, and there were other serious defects. For instance, a preliminary precipitation of the coarser impurities is important; this was not effected in the old machines, therefore the impurities, and particularly the coarser impurities, were constantly accumulating in the washer and clogging it. Even where this clogging did not absolutely block the machine, yet it caused a constant variation in the pressure rendering a gas holder necessary in all these old processes. Whereas in my process the pressure is absolutely constant and the gas holder is not necessary for regu-

lating the pressure (though often it is convenient for storing the cleaned gas).

A desirable mechanism for practicing my process is shown in the drawing herewith in which the reference letters of the description indicate the corresponding parts in the different views.

Figure 1 shows the cooler conveniently arranged in combination with the washer—the cooler in vertical, longitudinal section and the washer in vertical cross section. Fig. 2 is a vertical cross section of the washer taken at a right angle to Fig. 1. Fig. 3 is an elevation of the drum detached.

15. In the drawing, A indicates the gas cooler and B the gas washer. The cooler is desirably formed of a metal cylinder C suitably supported on legs or brackets D and having its open lower end extending into a water seal 20 E from which the water flows away in a channel or pipe F, and having its upper end closed by a cover H.

K is a sprinkler having a plurality of nozzles J supplied through pipe G having valve 25 L with water from any suitable source of supply.

30. O are valves for more or less of the separate nozzles, to control, regulate and distribute the water. The hot gases enter the cylinder through pipe N, over which is arranged a conical shield P, spreading the gas and forcing it to pass through the water flowing over the edges of the shield, thus giving up heat initially and the heavier impurities are precipitated into the water seal. The gases thence pass up into the cylinder through the contracted central opening in the circumferential inclined shelf Q, passing a second time through a circular stream of water, to be 35 further cooled, moistened and incidentally cleansed. In the upper part of the cylinder the gases are further cooled and moistened to the necessary degree in the dense shower of cold water. By this arrangement the greatest effect of the cooling water is obtained and the gases are prepared as aforesaid in the proper condition for the remaining steps of the process. The circular streams of water in the bottom of the cooler, are somewhat 40 warmed and dirty above, but are useful as aforesaid.

45. The cooled and moistened gas passes from the cooler through pipes M and R to enlarged junction S; its course being turned an angle, it is slightly checked so that the heavier impurities are not carried into the washer but fall by gravity into the water seal 16, whence they may be removed from time to time, and all danger of clogging the washer at this point 50 avoided. At the top of pipe R may be arranged a second sprinkler T further to cool, moisten and clean the gas.

55. The washer consists of a casing 1, cylindrical, or tapering from larger at front or gas admission end to smaller at rear or exit end,

suitably supported as on standards 2, in which is journaled shaft 4 having a pulley 7 or other means, for application of power, and carrying the rotating drum 11, cylindrical in form, or tapering to correspond with the casing, which is provided on its exterior with wings $a a' a''$, $b b' b''$, arranged inclined (or spirally) to throw the water centrifugally and to drive it in the reverse direction to the flow of the gas. The interior of the casing 70 is provided with strips 9 forming projections, to check the film of water flowing around in contact with the casing and to bring it in proximity to the wings, whereby the water is continually being broken up, forming a plurality of showers or veils of water flowing over the rear edges of the wings through which the gas is forced to pass. The effect of the wings is also constantly to return the impurities mixed with the water-mist to said 75 solid film, which is constantly flowing toward the front and the water outlet, in the channels formed between the strips, carrying out the impurities.

80. The wings are preferably arranged as shown, at the front less inclined to the axis, and being gradually more inclined toward the rear, and in two series of alternately arranged sets of different inclinations, whereby at the front their effect is more centrifugal 85 and less to force the water longitudinally, whereby there is the greatest formation of fine water-mist and admixture thereof with the gas to unite with the impurities and then deliver them into the film of water on the inner surface of the shell constantly flowing forward; but toward the rear the reverse, less centrifugal and more longitudinal effect, whereby the water is more rapidly forced forward, and better separated from the gas sufficiently to dry the gas. The wings being arranged in detached sets, sheets of water mist are formed between the front edge of each and the preceding wing, through which the gas is rapidly drawn insuring contact of all 90 the gas with the maximum of water-mist, and effecting practically perfect cleansing of the gas before it passes out to the engine.

95. On the shaft or drum is arranged in the enlarged end 20 of the casing the fan 21 to draw the gases through the cooler and the washer and to deliver them through the outlet to the delivery pipe by which they are conducted to the engine or elsewhere usefully to be consumed.

100. 13 is the water inlet and 16 a seal to receive the dirty water. 29 is a second water seal to receive from pipe 30 the drip of the trifling amount of water that sometimes collects in the fan casing, particularly when the 105 machine is stopped.

110. The term water-mist is used here to distinguish the finest spray formed by mechanical means from vapor or steam formed by heat. In the cooler only the coarse spray, like rain, 115

is desired to cool and moisten the gas, but in the washer the fine water mist to unite with all the impurities and completely wash them out.

As indicated, the gas is first cooled and moistened in the cooler, for the purposes described. As it reaches the inlet to the washer, its direction is changed to separate out by gravity some of the impurities, and then, immediately at the inlet into the washer, arranged at the circumference and below, it meets a downpour or shower of water mist driven forcibly in exactly the opposite direction to the entering gases, whereby the gas is further moistened and more impurities are separated out. It will be understood that all this preliminary cleansing relates more to the coarser impurities, and though such cleansing effect is only partial, it is important, to prevent the entrance of those coarser impurities into the washer so far as possible, which avoids the danger of clogging the washer and increases its efficiency, permitting the use of the smallest size washer with the minimum of water, and the completion of the process in the shortest time. For as large quantities of gases are being treated, they must be washed not only perfectly, but quickly and economically. The gas is being drawn through the entire apparatus often at a speed of 500' per minute or more. After the gas has entered the washer, it is throughout the entire length thereof being subjected to the cleansing action of the sheets of water-mist; this mist is constantly being formed by the wings and constantly being returned centrifugally thereby, carrying with it the impurities it has absorbed or saturated into the water film constantly flowing toward the front between the strips. Toward the front of the machine the greatest cleansing effect is constantly going on, but toward the rear the effect is more that of separating out the water and drying the gas. These two steps or effects produced in the washer are dependent on and made possible by the preliminary step of cooling and moistening and of precipitating the coarser impurities.

Having thus described my invention, what I claim as new and desire to secure by Letters Patent, is:—

1. The herein described process of cleansing gases which consists in first cooling the gas and then drawing it through a stream of water, which is being driven in an opposite direction to the movement of the gas, and simultaneously being broken up into water-mist.

2. The herein described process of cleansing gases, which consists in first cooling and moistening the gas, by drawing it through a falling shower of water and then completing the cleansing of the gas by forcing it through a stream of water, which is being driven in an opposite direction to the gas and simultane-

ously being forced centrifugally and broken up into water-mist.

3. The herein described process of cleansing gases which consists in first cooling and moistening and partially cleansing the gas by drawing it upwardly through an elongated chamber filled with a falling spray of water, and then drawing it into and through a second chamber, in which a stream of water is being driven by a force which moves it both centrifugally and longitudinally, in a direction opposite to the flow of the gas and simultaneously breaks up the water into water-mist to a large extent, the direction of the flow of the gas being changed at the entrance to the second chamber, and the force being applied to the water adjacent to the gas inlet end of the second chamber so as to break it up and drive it centrifugally to a greater extent and to force it forward to less extent to commingle the water-mist with the gas, but adjacent to the opposite end of the chamber, less to force the water centrifugally and more to force it forwardly, whereby the water particles and impurities are separated from the gas and the gas dried.

4. The herein described process of thoroughly washing gases for gas engines which consists, continuously and successively in cooling and moistening the gas and washing out the heavy impurities by first forcing the gas through a shower of falling water and then through a stream of water broken up into the finest spray and driven substantially in the opposite direction to the gas, and then washing out the fine impurities by forcing the gas through a plurality of sheets of the fine spray.

5. A continuous process for thoroughly cleansing gases for the gas engine, which consists in forcing or drawing the gas rapidly forward so as to be subjected to the various steps of the process in rapid succession, as follows, first cooling and moistening the gas and precipitating some of the coarser impurities by subjecting the gas to a shower of cool water, then changing the direction of the flow of gas and subjecting it to a stream of water broken up into the finest spray and driven in exactly the opposite direction to the flow of the gas, to further precipitate the heavier impurities and to further cool and moisten the gas, and finally subjecting the gas to a plurality of sheets of said fine spray, formed within a film of water, said spray being formed by centrifugal force, whereby the spray mixed with impurities is constantly being forced centrifugally into the water film and the water film forced rearwardly to carry off the impurities.

6. The herein described process of washing gases for gas engines, which consists continuously and in succession in first cooling and moistening the gas by forcing it through a shower of falling water, then changing its

- direction of flow at a sharp angle to precipitate the heavier impurities, then drawing it through a stream of water subdivided into the finest spray and driven directly in the opposite direction to the gas, further to cool and moisten the gas and to precipitate the heavier impurities, and then washing out the fine impurities by forcing the gas through a plurality of sheets of the fine spray.
7. In a process for cleaning gases, the method of washing out the finer impurities which consists in forcing the gas through a chamber, and simultaneously maintaining a film of water in the chamber around the gas, forcing the water forward in the opposite direction to the gas, and breaking up the water by centrifugal force, whereby a plurality of sheets of water-mist are formed, through which the gas is forced to pass, and the water-mist mixed with the impurities are constantly being driven centrifugally into the film.

8. The herein described process of cleaning gas that consists as a continuous process in forcing the gas rapidly forward and subjecting it to the effect of water moving in the opposite direction to the gas, the process comprising a series of steps as follows: first subjecting the gas to falling streams of cold water, then to a falling shower of cold water, then changing the direction of the flow of the gas at a sharp angle, then subjecting the gas to a stream of water-mist driven forcibly against the gas, then passing the gas through a plurality of sheets of water-mist, then separating the moisture from the gas.

In testimony whereof I have signed my name to this specification in the presence of two subscribing witnesses.

GUSTAV SAALEER.
